BY *D. M. Jennings*
Watson E. Coleman
ATTORNEY.

UNITED STATES PATENT OFFICE.

DAVID MARION JENNINGS, OF WACO, TEXAS.

SWITCH-OPERATING MECHANISM.

Application filed January 5, 1924, Serial No. 684,610. Renewed April 9, 1925.

To all whom it may concern:

Be it known that I, DAVID MARION JENNINGS, a citizen of the United States, residing at Waco, in the county of McLennan and State of Texas, have invented certain new and useful Improvements in Switch-Operating Mechanism, of which the following is a specification, reference being had to the accompanying drawings.

10 This invention relates to switch operating mechanism and more particularly to devices of this character which are semi-automatic in their operation.

15 An important object of the invention is to provide in combination with a car carried positionable trip mechanism, mechanism engaged by the trip mechanism and which at each engagement by the trip mechanism reverses the position of the switch with which 20 it is associated.

25 A further object of the invention is to provide an operating mechanism of this character including a rotatable member which is partially rotated by each engagement of the trip, together with mechanism connecting the rotatable member and the switch which at each partial rotation of the operating mechanism reverses the position of the switch.

30 These and other objects I attain by the construction shown in the accompanying drawings, wherein for the purpose of illustration is shown a preferred embodiment of my invention and wherein:—

35 Figure 1 is a plan view partially in section showing switch operating mechanism constructed in accordance with my invention;

40 Figure 2 is a section on the line 2—2 of Figure 1;

Figure 3 is a section on the line 3—3 of Figure 1; and

45 Figure 4 is a detail view showing the mounting of the operating mechanism upon the car.

Referring now more particularly to the drawings, the numeral 10 generally designates a switch, and 11 the movable switch point thereof. In accordance with my invention I provide adjacent the switch a casing 12 buried in the ground so that its cover 13 is flush with the surface thereof. Within the casing is arranged a two-part guide member 14, the sections of which when assembled provide a substantially rectangular opening 15 in which is slidably mounted a

two-part block 16. The walls of the two-part guide 14 have formed through the side wall thereof an opening 17 aligning with an opening 18 formed in the corresponding wall of the casing, while at one end of the guide opening 15 the end wall of the casing is provided with an opening 19. Each part of the two-part block is provided with one-half of a shank portion 20, the completed shank being connected with an operating rod 21 by a coupling 22, the connection extending through the opening 19 of the casing 12.

Adjacent faces of the block sections are provided with arcuate slots or grooves 22 in which are engaged rollers 23 carried by the ends of a vertically disposed pivot 24 with which is engaged one end of a link 25. The opposite end of this link, which is directed through the opening 17 of the guide member and the opening 18 of the side wall of the casing, is pivotally connected with the switch point 11, as at 26. The formation of the slots is such that upon shifting of the block 16 longitudinally to a point such that the rollers 23 are engaged with the central portion thereof, the switch point 11 will be arranged at one extreme position, while when the rollers are engaged at either end of the slot the switch point will be in the other extreme position. Arranged alongside of the right of way at a point of predetermined distance in advance of the casing 12, a second casing 27 is buried in the ground having its cover 28 substantially flush therewith. This casing is provided at the end thereof next adjacent the casing 12 with an opening 29. Arranged within the casing are bearings 30 in which is rotatably mounted a shaft 31 bearing an eccentric 32 aligned with the opening 29 of the casing. To the strip 33 of this eccentric is connected the free end of the operating rod 21. Likewise secured to the shaft 31 is a disk 34, the periphery of which extends into a slot 35 formed through the cover 28 of the casing 27 and is provided with a plurality of notched teeth 36, each tooth being spaced from the next adjacent tooth a distance equal to one-quarter of the diameter of the disk.

It is intended that the last described mechanism should be operated through the engagement with the ratchet disk 34 of an element carried by a car operating upon the tracks and released by the operator of the car when it is desired that the position of the switch be changed. In the present in-

stance I have diagrammatically illustrated an apparatus of this character consisting of an arm 37 carried by the car and movable to the elevated or depressed position. This arm has mounted in its lower end a dog 38 having a tooth 39 for engagement with the teeth 36 of the disk 34, the dog being provided with a striker wheel 40 preventing its engagement with the ground prior to its engagement with the disk. The dog is preferably yieldably mounted, as indicated at 41, so as to prevent too sudden a jerk being applied to the mechanism. The operating rod 21 is preferably housed, as at 42, by a tubular member connecting the housings 12 and 27. It will be obvious that by the use of mechanism constructed in accordance with my invention a switch may be alternated between the two positions as desired and will be positively held in such positions. It will furthermore be obvious that by constructing the mechanism as hereinbefore set forth the same may be readily assembled and repaired. It will, of course, be obvious that the construction set forth is capable of some change and modification without in any manner departing from the spirit of my invention and I accordingly do not limit myself to such specific structure as hereinbefore set forth except as hereinafter claimed.

I claim:—

1. In a device of the type described and in combination with a railway switch embodying a shiftable point, a guide arranged adja-

cent the switch, a longitudinally shiftable block mounted in the guide and having a longitudinally disposed arcuately curved slot, car operated means for shifting said block, a roller operating in the groove of said block and held against movement longitudinally of the block, a link connecting said roller and the point of said switch, the car operated means including an eccentric having a strap, a link connecting the strap and block, and means for partially rotating said eccentric.

2. In a device of the type described and in combination with a railway switch embodying a shiftable point, a guide arranged adjacent the switch, a longitudinally shiftable block mounted in the guide and having a longitudinally disposed arcuately curved slot, car operated means for shifting said block, a roller operating in the groove of said block and held against movement longitudinally of the block, a link connecting said roller and the point of said switch, the car operated means including an eccentric having a strap, a link connecting the strap and block, means for partially rotating said eccentric, comprising a ratchet wheel secured to said shaft, and a car carried dog shiftable to engage said ratchet wheel and to rotate the same through the one step during passage of the car.

In testimony whereof I hereunto affix my signature.

DAVID MARION JENNINGS.
